(57) **CLAIM**

The ornamental design for furniture for a commercial aircraft passenger cabin, as shown and described.

DESCRIPTION

FIG. 1 is a front-left side perspective view of furniture for a commercial aircraft passenger cabin according to my design; FIG. 2 is a top plan view thereof;

FIG. 3 is a right side elevation view thereof;

FIG. 4 is a left side elevation view thereof;

FIG. 5 is a front elevation view thereof;

FIG. 6 is a rear elevation view thereof;

FIG. 7 is a front-left side perspective view of furniture of FIG. 1 shown in a commercial aircraft passenger cabin; and,

FIG. 8 is a top view of furniture and cabin shown in FIG. 7.

No bottom plan view is included as no features of the claimed design are visible therein.

Throughout the Figures, the broken lines and non-shaded areas showing environment or structure are for illustrative purposes only and form no part of the claimed design. Dash-dot broken lines represent the boundary between claimed and unclaimed areas and form no part of the claimed design. Dotted lines represent elements of the environment and form no part of the claimed design.
